CLAIM

The ornamental design for an e-liquid dispenser case, as shown and described.

DESCRIPTION

FIG. 1 is a front elevational view of an e-liquid dispenser case, showing our new design.

FIG. 2 is a left side elevational view thereof.

FIG. 3 is a right side elevational view thereof.

FIG. 4 is a top perspective view thereof.

FIG. 5 is a rear perspective view thereof.

FIG. 6 is a bottom perspective view thereof.

FIG. 7 is a front elevational view thereof.

FIG. 8 is a rear elevational view thereof.

FIG. 9 is a left side elevational view thereof.

FIG. 10 is a right side elevational view thereof.

FIG. 11 is a top plan view thereof; and,

FIG. 12 is a bottom plan view thereof.

The broken lines in the drawings depict parts of the e-liquid dispenser case that form no part of the claimed design.
